No. 857,191.

PATENTED JUNE 18, 1907.

F. W. NEWELL.
AUTOMATIC MOTOR CONTROLLING APPARATUS.
APPLICATION FILED NOV. 13, 1905.

UNITED STATES PATENT OFFICE.

FREDERICK W. NEWELL, OF HASTINGS-UPON-HUDSON, NEW YORK, AS
SIGNOR TO OTIS ELEVATOR COMPANY, OF JERSEY CITY, NEW JERSEY,
A CORPORATION OF NEW JERSEY.

AUTOMATIC MOTOR-CONTROLLING APPARATUS.

No. 857,191.

Specification of Letters Patent.

Patented June 18, 1907.

Application filed November 13, 1905. Serial No. 286,998.

To all whom it may concern:

Be it known that I, FREDERICK W. NEWELL, a citizen of the United States, residing at Hastings-upon-Hudson, in the county of 5 Westchester and State of New York, have invented a new and useful Improvement in Automatic Motor-Controlling Apparatus, of which the following is a specification.

My invention relates to motor-controlling means and one of its objects is the provision of simple and efficient means for slowing down the speed of an electric motor when said motor is run by some mechanical means, such as the load of an elevator overrunning 15 its gear.

Other objects of the invention will appear hereinafter, the novel combinations of elements being pointed out in the claims.

In the accompanying drawings Figure 1 20 represents diagrammatically a system of circuits and apparatus for slowing down an electric motor which may be employed to operate elevator apparatus; and Fig. 2 represents diagrammatically my invention when employed 25 as a means for stopping an electric motor.

Referring to Fig. 1, L designates a two-pole main line switch connected to the mains + and -. An elevator car is diagrammatically represented at C and in the car is a 30 manually actuated switch O which is electrically connected to the reversing switch R. Any suitable hoisting apparatus driven by the motor M may be used to operate the car.

Associated with the motor-armature are the accelerating magnet A, series field S and starting resistance 1, and shunt field F. 2 35 designates a relay for automatically controlling the resistances 3 and 4.

The reversing switch R comprises a lever 5 40 which is pivoted at 6 and normally held in central position by the springs 7 and 8. At 9 to the upper or outer end of the lever 5 is pivoted the rod 10, said rod connecting the cores 11 and 11', which are adapted to be actuated by the solenoids 12 and 12'. These 45 solenoids are connected by means of the wires 75 and 75' to the fixed contacts 13 and 13', respectively, of the operating switch O. Adapted to engage either of these contacts is 50 a switch lever 14, which is electrically connected by wire 42 to the main 21.

The reversing switch lever 5 comprises the insulated bridge pieces 15 and 16, the bridge piece 15 being arranged to connect contacts

17, 18, or the contacts 17', 19', and the 55 bridge piece 16 being adapted to connect the contacts 19, 20, or the contacts 18', 20'. These contacts are suitably connected to the motor M, the resistances 3 and 4 and the series field S.

The relay 2 comprises a coil 22 wound on the core 23 and connected directly across the mains 21 and 36 by means of the wire 24. This wire 24 is also connected at the points 25 and 25' to solenoids 12 and 12'. Also 60 wound on the core 23 is a coil 27, which is connected to the positive main 21 at 40, and also to the resistance 3. The core 23 is adapted to act on the armature 43, which is pivoted at 44 to move contact 45, carried by 65 the armature-lever, into engagement with the fixed contact 46.

The shunt field is connected across the mains between the points 40, 41 by means of the wires 38 and 39, and accelerating magnet 75 A is connected directly across the motor-armature.

In the operation of the system shown in Fig. 1 the main line switch L is closed, whereupon the coil 22 receives current to energize 80 its core 23 to effect the engagement of the contacts 45 and 46. The shunt field F will also be excited. If the switch lever 14 is moved to the right so as to engage the contact 13, a circuit will be established from 85 main 21, through wire 42, the switch lever 14, contact 13, wire 75, solenoid 12, wire 24 to the negative main 36. The coil 12 will therefore be energized to move its core 11, and consequently the reversing switch lever 5 to 90 the left so as to connect contacts 17 and 18, and also the contacts 19 and 20. A circuit will now be established through the motor armature, which may be traced from the positive main 21 through the winding 27 of 95 the relay 2, contacts 46 and 45, wire 48, wire 28, contact 17, bridge piece 15, contact 18, wire 33, armature brush 32, armature 31, brush 30, wire 29, contact 19, bridge piece 16, contact 20, wires 34 and 35, series field S, starting resistance 1 and the negative main 36. The motor M will now start and operate the hoisting apparatus to move the car up or down as desired. If it is desired to operate the motor in the opposite direction, switch 14 100 is brought on to the contact 13', whereupon the solenoid 12' will be energized to move the reversing switch lever 5 to its right-hand posi-

60

105

tion to connect the contacts 17', 19' and also the contacts 18', 20', thereby reversing the direction of current through the motor-armature 31 to move the car in the opposite direction. As the motor increases in speed the energization of the accelerating magnet A is gradually increased to successively operate the switches 37 to cut out or short circuit the series field S and the resistance 1 10 step-by-step in the well-known manner.

It should be noted that the winding 27 assists the winding 22 in energizing the core 23, causing the latter to hold the armature 43 in its upper position so long as current is flowing from the main 21 through said coils to the wire 24 and resistance 3, respectively. Should the car C attain an excessive speed and thereby drive the motor M forward, or as a generator, current will be sent back into 15 the line through coil 27 in a direction opposite to that in which the current flowed therethrough when the motor M was doing work. The coil 27 will therefore neutralize the effect of the coil 22 and allow the armature 43 to drop, so as to disconnect contacts 45 and 46 and insert resistance 3 in circuit with the motor M, which is now acting as a generator. This will have the effect of reducing the amount of current which would otherwise be 20 sent out to the line and also to shunt more current through the resistance 4, which is placed across the motor-armature 31 by the engagement of the contacts 45 and 47. This local circuit comprising the resistance 4 and 25 armature 31, will constitute an electro-dynamic brake, and may be traced from brush 32 through wire 33, contact 18, bridge piece 35, contact 17, wires 28 and 48, contacts 45 30 and 47, resistance 4, wire 34, contact 20, bridge piece 16, contact 19 and wire 29 to brush 30. The ultimate effect of the insertion 35 of the resistance 3 and the establishment of the electro-dynamic brake circuit will be to immediately bring the motor M to a slow 40 speed or to such a speed where the main line potential again acts to drive the motor M and cause the same to do work. When the motor M again receives current from the line the armature 43 will be automatically lifted by 45 the differentially-wound relay magnet to disconnect the contacts 45 and 47 and connect the contacts 45 and 46, so that the system 50 will again assume its normal operation.

In Fig. 2 I have shown a relay 2' which is 55 similar to the relay 2 of Fig. 1, in that it is doubly wound and is connected in a similar manner, but instead of controlling resistances, as 3, 4 of Fig. 1, said relay controls one of its own windings. 60 50 designates a main lineswitch which, in this instance, is shown provided with manual means 62 for initially closing said switch by moving the contacts 53, 70 and 71 into engagement with the fixed contacts 50 and 72. 65 A current will then flow from the positive

main to contacts 52 and 53 and by way of wire 21' through solenoid 22' and wire 24' to wire 36', and thence through contacts 71 and 72 to the negative main. The core 23', will therefore be magnetized to attract its armature 43' against the action of the spring 55' to move the contact 45' into engagement with the fixed contact 56. The lever 77 carrying the armature 43' is pivoted at 44' and normally held in its right hand position, as 70 shown, by the spring 55. By the closure of the switch 50 a circuit will also be established through coil 27', wire 76, brush 30, armature 31, brush 32, resistance 1, series field S and thence by wire 36' to the negative 75 main. The winding 27' like that designated 27 in Fig. 1, is of low resistance, while that designated 22' (or 22 in Fig. 1), is of comparatively high resistance, and the winding 27' is wound to normally assist the winding 80 22' in magnetizing the core 23'. As soon as the contacts 45' and 56 are placed in engagement with each other a circuit is closed from the point 58 through the coil 54, wire 51, armature lever 77, contacts 45' and 56, wires 57, 24' and 36' to the negative main. This circuit constitutes a retaining or holding circuit for the switch 50, for, as soon as the switch 50 is closed manually by means of a handle 62, the relay 2', is operated to effect the excitation of the coil 54, which then acts on its core 59 to hold the same in its uppermost position, and consequently the contacts of the switch 50 in firm engagement with each other. The movable contacts 53, 100 70 and 71 are insulated from each other by the bar or plate of insulation 61 to which they are secured and by which they are carried. This bar or plate 61 is rigidly attached to the upper end of the stem 60, which is carried by 105 the core 59.

When switch 50 is closed and held closed in the manner stated a circuit is also established from the positive main through wire 63, shunt field F and wires 64 and 36' to the 110 negative main. Also, a circuit is closed from the positive main through wire 67, brake-magnet solenoid 68, wire 69, to the negative main. The excitation of the coil 68 will cause its core 73 to be lifted to release the 115 brake by means of the stem 74 which is connected between the core 73 and the brake-applying means, which may be of any well known type.

The motor may now start and, if desired, 120 accelerating apparatus, as shown in Fig. 1, may be used in connection therewith to gradually cut out the resistance 1 and series field S, so that the motor may start with a strong torque as a compound-wound motor, 125 and after being started and run to full speed, thereafter operate as a shunt-wound motor.

Should the load connected to the motor M, as for instance an elevator car and hoisting mechanism therefor, operate such motor as a 130

generator, current would be sent by said generator through the coil 27' in an opposite direction and thence back into the line. Part of such current would be shunted through the coil 22', but it should be noted that when current passes through these two coils 27' and 22' in series instead of in parallel, as normally, said coils will neutralize each other's magnetism and the spring 55 will, therefore, 10 open the contacts 45', 56 and de-energize the magnet which holds the switch 50 closed while the motor M is acting as a motor. Upon the opening of the switch 50 the brake magnet will also be de-energized and effect 15 the application of the brake and the consequent stopping of the motor in an obvious manner.

In Fig. 2 I have shown manual means for closing switch 50 initially, which must also be 20 used after the said switch has been opened automatically in the manner explained. In Fig. 1, however, the construction illustrates apparatus for slowing down the motor if it acts as a generator, and then automatically 25 again increasing its speed if the motor receives current and does work.

The subject-matter disclosed in Fig. 2 and not herein claimed is covered in my co-pending application Serial No. 346,391, improvement 30 in electro-dynamic brakes, filed December 5, 1906, as a division of this application.

It is obvious that those skilled in the art may make various modifications in the details and arrangement of parts without departing from the spirit and scope thereof. I therefore do not desire to be limited to the exact construction herein disclosed.

What I claim and desire to have protected by Letters Patent of the United States is:

40 1. The combination with a motor, of controlling apparatus therefor, a doubly-wound magnet having one winding connected across the mains and the other winding in circuit with the motor-armature, and electric means controlled by said magnet for regulating the speed of the motor.

2. The combination with a motor, of controlling apparatus therefor, a differentially-wound magnet having one winding connected 50 across the mains and another winding in circuit with the motor-armature; and electric means controlled by said magnet for slowing down said motor when excessive speed is attained.

55 3. The combination with a motor, of starting means therefor, a differentially-wound relay having one winding connected across the mains and the other winding in series with the motor-armature, an electro-dynamic-brake circuit, and means controlled by said relay for closing said circuit when the motor acts as a generator.

4. The combination with a motor, of reversing switches therefor, a differential relay 60 having one winding connected to the mains

and the other winding in a normally open circuit with the motor-armature, means controlled by said relay for regulating the speed of said motor, and means for operating said reversing switches to close said normally 70 open circuit and effect a starting of the motor in the desired direction.

5. The combination with the motor, of controlling means therefor, a doubly-wound electro-magnet, a plurality of resistances, and means controlled by said electro-magnet for inserting one of said resistances in series with the motor-armature, and another of said resistances in shunt thereto.

6. The combination with an electric motor, 80 of controlling apparatus therefor, a doubly-wound magnet, two resistances, and means controlled by said magnet for inserting one of said resistances in series with the motor-armature and the other in shunt thereto, when the 85 motor acts as a generator.

7. The combination with an electric motor, of controlling apparatus therefor, a differentially-wound magnet, a resistance normally 90 in series with one of the windings of said magnet, an additional resistance, and means controlled by said magnet for inserting said first-named resistance in series with the motor-armature, and said additional resistance in shunt thereto.

95 8. The combination with an electric motor, of controlling apparatus therefor, a differential relay having one winding connected to the mains and the other winding in series with the motor-armature, a resistance normally 100 short-circuited by said relay, and an additional resistance inserted in shunt to the motor-armature upon the neutralization of the magnetism in the relay-magnet and the consequent insertion of said first-named resistance 105 in series with the motor-armature.

9. The combination with an electric motor, of controlling apparatus therefor, a differentially-wound magnet having one winding of comparatively high resistance and connected 110 directly across the mains and another winding of low resistance arranged to be connected in series with the motor-armature, a resistance in series of the low resistance winding, an additional resistance, and means controlled by said magnet for short-circuiting 115 said first-named resistance and cutting out said additional resistance when said magnet is energized and for inserting said first-named resistance in series with the motor-armature 120 and said additional resistance in shunt thereto when the motor is acting as a generator and said magnet is de-energized.

In testimony whereof, I have signed my name to this specification in the presence of 125 two subscribing witnesses.

FREDERICK W. NEWELL,
Witnesses:

W. M. E. MYERS,
CHARLES B. MANVILLE.
